UNITED STATES PATENT OFFICE

2,575,495

BRUSH MOISTENER

August C. Hummel, Cincinnati, Ohio

Application March 9, 1950, Serial No. 148,535

6 Claims. (Cl. 91—38)

1

My invention relates to a brush moistener of the type used for moistening adhesive coated paper labels or tape and of the type generally shown and described in my copending application Serial No. 624,368, filed October 25, 1945 and entitled Moistening Brush and Holder, which issued as Patent No. 2,504,690, April 18, 1950.

Recently, it has become the practice in numerous stores for the clerks to wrap and address parcels which are purchased and which are to be delivered. In doing this, the clerk tears off a portion of the sales slip carrying the name and address of the customer and fastens the torn off portion to the package or carton by means of a strip of paper or tape containing moistened adhesive on both sides so that one side adheres to the container and the other side adheres to the ticket containing the address.

My invention particularly relates to a brush moistener which easily and quickly moistens both sides of a double sided adhesive tape or label at the same time.

It is an object of my invention to provide such a brush moistener which will moisten both sides of the tape or label, while it is being slipped through the moistener.

A further object of my invention is to provide a moistener as set forth above which may be easily and quickly opened so that the brush and container may be cleaned or refilled with water.

A further object of my invention is to provide a moistener with all of the above enumerated features and wherein the moistening surfaces may be quickly and easily replaced or removed for cleaning. A further object of my invention is to provide a moistener as described above which is extremely compact, relatively inexpensive to construct, but which is extremely rugged and susceptible of continuous use without deterioration or the necessity of constant adjustment and cleaning.

These and other objects of my invention which will be set forth hereinafter or will be apparent to one skilled in the art upon reading these specifications, I accomplish by that certain construction and arrangement of parts of which I shall now describe an exemplary embodiment. Reference is now made to the drawings which form a part thereof and in which:

Figure 1 is a plan view of my novel brush moistener.

Figure 2 is a vertical cross section of the moistener shown in Figure 1 taken on the section line 2—2 of Figure 1.

2

Figure 3 is a cross section of the moistening end of the cover portion exploded.

Figure 4 is a perspective view of the cover with the supplemental moistening attachment in exploded condition.

Briefly, in the practice of my invention, I provide a moistener of the type shown in my copending application, Serial No. 624,368 wherein a fountain brush bears against the leading edge of a cover plate so as to moisten one side of a tape slid under the tape guide. However, I provide a porous strip which covers the underside of this tape guide and is kept in a moistened condition by the capillary action of the brush and strip when they are in contact. The porous strip is preferably wrapped around the tape guide and held in place by a clamping strip which in turn is held by removable nuts so that removal and replacement of the porous tape is extremely easy.

As a piece of tape or label carrying a water soluble adhesive on both surfaces is passed under the tape guide, the end of the brush moistens the bottom surface while the moist porous strip moistens the top surface. The strip or label may be torn off in the usual manner, if desirable, against the leading edge of the tape guide in a similar manner as in copending application, Serial No. 624,368.

Referring to the drawings, I provide a water container 1 having a cover plate 2 either hinged to the container by the pintles 3 or resting within the container as shown in my copending application, Serial No. 624,368.

The leading edge of the plate 2 carries a tape guide strip 4 under which the tape or label 5 passes.

Within the container 1 I provide a brush 6 with its base 7 submerged in water 8 and with its end 9 projecting upwardly out of the water 8 in case 1, and positioned under the leading edge of the plate 2 as exemplified by the tape guide 4.

Embracing the tape guide 4, I provide a strip 10 of porous material which has a portion underlying the tape guide strip 4 and so arranged as to be in resilient contact with the brush end 9.

I preferably pass the porous strip 10 around the trailing edge of the tape guide 4 and up over on the top of the tape guide 4. A clamping strip 11 of substantially the same size and configuration as the tape guide strip 4 is placed on top of the overlying portion of the porous strip 10. Bolts 12 project upwardly from the cover portion 2 and run through holes 4' in the tape guide and 11' in the clamping strip 11. They may be spaced apart by collars 13.

The ends of the bolts 12 project beyond the clamp bar 11 and the assembly is drawn together, clamping a portion of the porous strip 10 between the tape guide 4 and the clamp bar 11 by nuts 14 placed on the ends of bolts 12.

In the event, the porous strip 10 is of appreciable thickness, I preferably space the tape guide 4 from the plane of the cover plate 2 by means of nuts or spacers 15 so as to provide a slot 16 between the lower surface of the porous strip 10 and the surface of the plate 2 to permit the easy insertion of the tape 5 between the brush end 9 and the porous strip 10.

From the above, it is apparent that when no strip 5 is being passed through the device, the moist end 9 of the brush 6 is in contact with the lower surface of the porous strip 10 and hence the porous strip 10 absorbs moisture and is dampened by the brush end 9.

When a strip 5 is slipped along the surface of the plate 2 and through the slot 16 and under the moist porous strip 10 and over the brush end 9, both surfaces of the strip 5 are moistened, the upper surface by the moistened porous strip 10 and the lower surface by the moist brush end 9.

In order to refill the container 1 with water 8, it is merely necessary to either remove the cover plate 2 or lift it upwardly, as shown in the broken lines in Figure 2. In this position, the brush 6 is available for removal, if desirable, and the well of the container 1 may be filled with water 8.

When it is desirable to remove the porous strip 10, it is merely necessary to remove the nuts 14 and lift over the clamping plate 11. This releases the porous strip 10 which may be inverted or reversed, if it still has a clean surface or a new porous strip 10 may be inserted in place, as is apparent from the drawings, the clamp bar 11 being returned into position and the nuts 14 replaced.

From the above, it is apparent that I have provided a moistener which is extremely simple in construction and wherein the moistening portions themselves may be easily removed for cleaning or replacement.

It is also apparent that I have provided a moistener of simple construction which easily and quickly moistens both surfaces of a tape or a strip which is passed therethrough.

It is to be understood that modification may be made in my invention without departing from the spirit thereof and I do not intend to limit myself otherwise than as pointed out in the claims which follow.

Having thus described my invention, what I claim as new and desire to secure by Letters Patent is:

1. In an adhesive tape moistener of the class wherein a fountain brush projects upwardly out of a water container having a cover plate including a tape guide resting on the fountain brush end and under which tape is adapted to slide so as to be moistened by the water on the brush end, the combination with said tape guide of a porous strip covering at least the portion of the tape guide resting on the fountain brush so that water from the brush is absorbed by and moistens said porous strip, thus moistening the tape on both surfaces when it is slid between the porous strip and the brush end, said tape guide comprising a strip spaced away from said cover plate to provide a tape receiving slot and said porous strip comprising felted material covering the bottom of said tape guide and projecting upwardly through said tape receiving slot and folded over

the top of said guide strip and retained in position by means on top of said guide strip, said means comprising a clamp bar positioned over the guide strip and clamping a portion of the felted material between the bar and the guide strip.

2. A cover plate adapted to be supported within a water containing casing and being of less width than the casing, said plate having angle pieces of less length than the casing secured thereto and providing flanges for projecting into the casing, a second plate mounted on the projecting portions above, beyond and parallel to the forward edge of the first mentioned plate and a third plate substantially coextensive with and mounted above said second plate with moisture absorbing felted material clamped between said second and third plate and with a trailing portion projecting downwardly between said first and second plate and against the bottom surface of said second plate and means for moistening said trailing portion of said felted material so as to provide a guide and moistener under which objects laid on the first plate may be slipped.

3. A cover plate adapted to be supported within a water containing casing and being of less width than the casing, said plate having angle pieces of less length than the casing secured thereto and providing flanges for projecting into the casing, a second plate mounted on the projecting portions above, beyond and parallel to the forward edge of the first mentioned plate and a third plate substantially coextensive with and removably bolted on top of said second plate, moisture absorbing felted material clamped between said second and third plate and with a trailing portion projecting downwardly between said first and second plate and against the bottom surface of said second plate and means for moistening said trailing portion of said felted material so as to provide a guide and moistener under which objects laid on the first plate may be slipped.

4. A cover plate adapted to be supported within a water containing casing and being of less width than the casing, said plate having angle pieces of less length than the casing secured thereto and providing flanges for projecting into the casing, a second plate mounted on the projecting portions above, beyond and parallel to the forward edge of the first mentioned plate and a third plate substantially coextensive with and mounted above said second plate with moisture absorbing felted material clamped between said second and third plate and with a trailing portion projecting downwardly between said first and second plate and against the bottom surface of said second plate so as to provide a guide and moistener under which objects laid on the first plate may be slipped, and a brush within said casing with the ends of its bristles contacting the felted material under said second plate.

5. A cover plate adapted to be supported within a water containing casing and being of less width than the casing, said plate having angle pieces of less length than the casing secured thereto and providing flanges for projecting into the casing, a second plate mounted on the projecting portions above, beyond and parallel to the forward edge of the first mentioned plate and a third plate substantially coextensive with and mounted above said second plate with moisture absorbing felted material clamped between said second and third plate and with a trailing portion projecting downwardly between said first and second plate and under said second plate and means for moisten-

ing said trailing portion of said felted material, so as to provide a guide and moistener under which objects laid on the first plate may be slipped, said felted material being sandwiched between said second and third plates and substantially covering the bottom of said second plate.

6. A cover plate for the purpose described comprising a substantially large plate, two small plates of similar shape mounted one upon the other and with felted material sandwiched therebetween, said latter plates being mounted beyond one edge of the first plate and in a plane slightly above the same, a trailing portion of the felted material projecting down through the space between the first plate and the other plates and un-

derlying the stacked plates and means for moistening said trailing portion of said felted material, so that articles placed on the first plate may be slid under the second plates and in contact with the felted material.
